UNITED STATES PATENT OFFICE.

PHILLIP SHERIDAN KIRBY, OF DENVER, COLORADO.

EMBROIDERY-NEEDLE.

1,396,849.

Specification of Letters Patent. Patented Nov. 15, 1921.

Application filed April 13, 1920. Serial No. 373,584.

To all whom it may concern:

Be it known that I, PHILLIP SHERIDAN KIRBY, a citizen of the United States, residing at Denver, in the county of Denver and 5 State of Colorado, have invented certain new and useful Improvements in Embroidery-Needles; and I do hereby declare the following to be a full, clear, and exact description of the invention, such as will enable 10 others skilled in the art to which it appertains to make and use the same.

My invention relates to art needles or embroidery needles, and more especially to such as are hand actuated, for producing ornamental designs upon one or both sides of a fabric base by means of loops formed successively through such base in a predetermined 15 design or pattern.

It has for an object the production of 20 needles of the class described, of extreme simplicity and efficiency, also the combination therewith of a gage element, for accurately and precisely regulating the depth of needle penetration, and consequently the extent of loops formed upon the under side of 25 the fabric base.

A further object is that of combining with 30 art needles of the class described an adjustable tension element for producing more or less tension upon the embroidery thread during the operation.

A further object is the production of improved needles of the character indicated 35 consisting in the novel construction, arrangement and combination of parts shown by the drawings forming part of the present application, hereinafter described.

In the drawings herewith submitted and 40 whereon corresponding characters refer to like parts in the several views:

Figure 1 is a side elevation of my present invention threaded and ready for use;

Fig. 2 is a longitudinal central section thereof;

Fig. 3 is a top plan view of the same;

Fig. 4 is a rear view;

Fig. 5 is a transverse section taken on the line 5—5 of Fig. 1; and

Fig. 6 is a detail detached view in perspective of a combined depth gage and tension spring.

Reference being had to the drawings and numerals thereon, 1 indicates the needle body preferably constructed of sheet metal and of substantially tubular or hollow formation. 55 This body portion 1 is substantially U-

shaped in cross-section except at and near its upper end, where its sides are crimped together as at 2, leaving however, an end thread-opening 3 therein. The sides of said body portion 1 moreover, present relatively wide flattened surfaces 4 and 5, in the latter of which are two series of perforations one in transverse arrangement marked 6, and the other arranged longitudinally designated 65 by the numeral 7, both of said series being for purposes which will later appear.

Immediately below the body 1 and integral therewith, is a hollow pointed needle 8 provided with an eye 9, in its lower end, this 70 member being practically circular in cross section, while at approximately the point of juncture between said body 1 and needle 8, the back of the structure is broken by two thread openings 10, 10, the intervening metal 75 being bent inward to form a tension bridge 11 over which the embroidery material or thread 12 is passed as shown by Figs. 1, 2 and 3, thus exposing the thread at that particular location to view.

Surrounding the needle 8 at a point below 80 said bridge 11 is an adjustable depth gage 13, made of relatively stiff spring wire, which traverses one side of the needle in an upward direction as at 14, thence loops over the 85 back of the structure as at 15, from which point it is continued upwardly parallel with flattened side 5 as at 16 terminating in an angular bend 17 adapted to enter one of the adjusting holes 6 or 7 for adjustment purposes 90 as will now appear in a brief statement of use and operation.

Presuming that a needle has been threaded as indicated by Figs. 1, 2 and 3, the embroidery material or thread 12 passes longitudinally therethrough, over the tension bridge 11 where it is exposed to view and through the eye 9 of the needle.

Presuming also that the combined depth gage and tension spring is set as indicated 100 by Figs. 1, 2 and 3, it will be observed that the maximum of needle penetration is secured and that the loop 15 of the tension spring serves to bind the thread 12 upon bridge 11 with a moderate degree of pressure, also that such pressure may readily be increased as desired for certain classes of embroidery, by simply withdrawing the angular end 17 of said spring from the first of said transverse perforations 6, and placing same in the second or third thereof according to the degree of tension desired.

As to the matter of longitudinal or depth adjustment, it is quite obvious that same is accomplished by similarly transferring the said angular extremity 17 to one or the other 5 of the longitudinal holes 7 according to depth requirements.

The aforesaid adjustments having been made in accordance with the character and extent of the design to be produced, the 10 threaded needle 8 is then passed rapidly through the fabric base (not shown) in the ordinary and well understood manner, each time leaving a suitable loop or stitch upon the underside of said base (not shown) as a 15 part of the prearranged design to be subsequently trimmed with scissors or left untrimmed according to requirements of the particular design in the course of formation.

Having thus described one practical and

successful embodiment of my present invention what I now claim and desire to secure by Letters Patent is:—

An embroidery needle comprising in combination a tubular body and a pointed lower end, a tension bridge formed in said body member over which the embroidery thread must pass, a combined adjustable depth gage and tension spring arranged and adapted to cross said bridge transversely and to engage with its angular end either of a series 30 of transverse holes in said body member.

In testimony whereof I affix my signature, in presence of two subscribing witnesses.

PHILLIP SHERIDAN KIRBY.
